ASSIGNORS TO GENERAL MOTORS CORPORATION, OF DETROIT, MICHIGAN, A
CORPORATION OF DELAWARE.

CAR-LOADING SYSTEM.

1,394,038.

Specification of Letters Patent. Patented Oct. 18, 1921.

Application filed October 15, 1919. Serial No. 330,933.

To all whom it may concern:

Be it known that we, GILBERT P. MARINIER and EDWARD E. CHRYSLER, citizens of the United States, and residents of Pontiac, 5 Oakland county, State of Michigan, have invented certain new and useful Improvements in a Car-Loading System, of which the following is a specification.

Our invention relates to the packing or 10 loading of automobiles and similar vehicles into freight cars with the end in view of placing as many such vehicles as possible within the car and fastening the same securely in place, so that they will not move about and be injured during transportation; and the object thereof is to provide an improved car loading system in which the vehicles may be more conveniently placed in 15 two tiers one above the other, and more securely held in place during the transportation thereof, than has heretofore commonly been the case in car loading or "decking" systems as they are commonly called.

A further object of our invention is to 20 provide a car loading system wherein the elements made use of therein are more simple in construction than has heretofore commonly been the case, and which elements may be more readily and cheaply manufactured than has been the case with the elements or supports heretofore used in car loading systems.

A further object of our invention is to 25 provide a car loading system in which the supports or struts which support the automobiles, and the braces which co-operate with the struts as will hereinafter appear, are of such form and construction that they may be used a plurality of times; thus effecting a material saving in lumber and material necessary in cases where carloads of motor vehicles are frequently shipped to the same destination, it being contemplated that the receiver will return the struts, braces 30 and other members employed in securing the vehicles properly in place within the car.

A further object of our invention is to 35 provide a car loading system wherein the struts, braces, and other elements which co-operate to support the vehicles and prevent movement thereof relative to one another may be more conveniently fastened to the sides and bottom of the car, and more effectively held in place and braced against

longitudinal movement, than has heretofore 55 commonly been the case.

With the above and other objects of invention in view, our invention consists in the improved car loading system illustrated in the accompanying drawing and hereinafter 60 described and claimed, and in such variations and modifications thereof, within the scope of the concluding claims, as will be obvious to those skilled in the art to which our invention relates.

In the drawings wherein the preferred embodiment of our invention is illustrated:

Figure 1 is a view showing a freight car in outline, and illustrating the positions in which vehicles are held therein relative 70 to one another in the practice of our improved car loading system.

Fig. 2 is a fragmentary view showing the manner in which a vehicle is supported from the floor of the car, and the method of 75 bracing the supporting members or struts against movement longitudinally of the car.

Fig. 3 is a fragmentary perspective view showing the upper end of a supporting strut, and a brace co-operating therewith.

Fig. 4 is a detail perspective view showing the lower end of a supporting member or strut, and the manner in which it may be secured to a car floor.

Fig. 5 is a perspective view showing an 85 anchor plate whereby the free end of a flexible brace member may be anchored to the floor of the car.

Fig. 6 is a view showing a modified form of anchor plate.

Fig. 7 is a fragmentary perspective view showing a modified form of supporting member or cap for receiving the hub of the vehicle being shipped.

Fig. 8 is a view showing still another form 95 of anchor plate.

Fig. 9 is a view showing a detail of construction and operation of our invention.

Referring now to the drawings, the reference numerals 9, 10 designate two inclined 100 supporting or strut members extending upwardly from the floor of the car within which the vehicles are to be placed, and inward from the sides of the car, as best shown in Fig. 1; two such supporting or strut members being used to support the forward 105 axle and two other such supporting members being used to support the rear axle of

each motor vehicle packed within the car, and as many vehicles being arranged one in front of the other and longitudinally of the car as the length of the car will permit.

- 5 The several motor vehicles within each car are commonly arranged in tiers, one above the other, as clearly shown in Fig. 1, in order to thereby increase the carrying capacity of the car, and, while we will in 10 describing our invention refer particularly to strut members and other elements employed for supporting the upper tier of vehicles, both the upper and lower tiers may be supported by supporting elements differing from one another only as regard 15 their length or size, as clearly shown in the Fig. 1 of the drawing. In case the upper tier only is supported in accordance with our improved car loading system, then the 20 vehicles of the lower tier may rest directly upon the floor of the car, and may be secured in place by cleats engaging the wheels thereof, or in any other manner effective for the end to be attained.
- 25 The vehicles to be supported are supported through or by the outer ends of the hubs of the several wheels thereof, the upper ends of the strut members being adapted to support the said hubs and being shaped or provided with means for engaging the under- 30 side of the hubs, so that the weight of the vehicle is transmitted through the supporting or strut members to the floor of the car.
- The strut members are commonly in the 35 form of wooden bars of appropriate size and strength and are provided with metallic base members 11, 12; said base members being preferably formed from a suitable sheet metal blank and having flanges 13, see Fig. 40 4, in order that the lower ends of the strut members may be secured to the car floor by screws, nails or other fastening devices. It will be appreciated that these screws or 45 nails may be comparatively short, because of the thinness of the flanges 13, thereby providing a scheme in which the lower ends of the strut members may be more readily secured to the floor of the car, and with less injury to the car, than would be the case if 50 the lower ends of the struts were secured by nails long enough to pass diagonally downward through the lower end thereof and into the floor of the car.

The upper ends of the strut members may 55 fit in beneath and directly support the hubs of the wheels of the vehicle, should such a method of construction and support be desired. We prefer, however, to provide the upper ends of the supporting or strut members each with a metallic cap member as 60 shown at 14, 15, Fig. 1; said cap members being secured to the upper ends of the strut members and having each a seat within which the hub of the vehicle rests when 65 the vehicle is in place and supported by

supporting members. These cap members may be formed from sheet metal blanks by suitable bending and shaping operations, such being the case in the form or cap member shown in Fig. 3, or they may be in the 70 form of integral castings, as shown at 16 in Fig. 7.

In the form or cap member shown in Fig. 3 the blank from which the cap is formed is provided with portions adapted to be bent 75 upward to form arms 17, whereby a seat is provided between the said arms within which the end of the hub of the vehicle rests, as shown in Fig. 9, a suitable protecting lining 18 being preferably employed to 80 prevent the marring of the hub. In the form of our invention shown in Fig. 7 the integral cap 16 is provided with a semi-circular seat 19 for receiving the hub of the vehicle, this seat being commonly provided 85 with a lining, the same as shown in Fig. 3, to prevent injury to the hub.

The weight of the vehicle being supported is carried by the four inclined supporting or strut members as will be appreciated. In 90 order to prevent sidewise movement of the upper ends of these members, brace members 20, 21 are provided, one coöoperating with each strut member, and which brace members extend from the sides of the car in- 95 ward and are connected with the upper ends of the strut members. These brace members lie substantially in vertical planes passing through the strut members and through the axles of the vehicle, and their inner ends 100 are preferably provided with hollow brackets 22, 23 having ears 24, through which bolts 25 extend, as best shown in Fig. 3 of the drawings.

The arrangement of the parts as best 105 shown in Fig. 3 is preferably such that the bolts 25 pass through the ears 24, the cap members at the upper ends of the strut members, and the upper ends of the strut members themselves, thereby holding all of said 110 elements together when the parts are assembled, as will be appreciated.

The outer ends of the brace members are provided with hollow brackets 26, 27 quite 115 similar to the base members 11, 12, of the supporting or strut members, and they have flanges similar to the flanges 13 for facilitating the fastening of the ends of the braces to the sides of the car, although, the said brackets are smaller than the base members 120 because of the fact that the braces are commonly smaller in cross-section than the inclined support or strut members.

After a motor vehicle has been elevated 125 within a car and supported in proper position by four inclined supporting or strut members the free ends of the arms 17 between which the hubs of the vehicle lie, are bent downward over the hubs, as shown in Fig. 9, and flexible tension members 28, 29, 130

one associated with each of said strut members in the preferred use of our system, are passed from the floor of the car upward and about the hubs of the vehicle, and then downward to the floor of the car; the free ends of the said members being secured to the floor of the car at points spaced apart from one another and located one to the front and the other to the rear of the lower end of said 5 strut members, as best shown in Fig. 2.

These tension members therefore act to hold the hubs in place relative to the upper ends of the supporting or strut members, and at the same time prevent longitudinal or 10 fore and aft movement of said upper ends because of the bracing action due to the positions in which their lower ends are fastened to the floor of the car. Preferably these 15 tension members are in the form of double 20 strands of twisted wire, the ends of which are secured to the floor of the car by means of anchor plates 30 having holes to receive lag or other screws, and another hole 31 to receive the ends of the wire. After such a 25 form of flexible member has been passed over the hub of the vehicle, ears 32 extending from the arms or sides 17 of the supports for the hubs may be bent down over the 30 flexible member, as shown in Figs. 1 and 9, and the flexible member then tightened by twisting the strands of the double wire as by means of a stick 33 shown in Fig. 2, during which operation the hubs will be 35 drawn tightly into the seats provided for their reception and a stiff and rigid bracing for preventing fore and aft movement of the upper ends for the supporting or strut members will be secured. The free ends of 40 the sticks contact with the strut members to thereby prevent the flexible members from untwisting, as will be understood, after the said members have been twisted to the extent necessary to secure a sufficient holding and bracing action.

45 Fig. 6 shows a form of our invention in which a single flexible tension member 34 is employed, the same being connected with an eye bolt 35 extending through a hole in the end of a slightly modified form of anchor 50 plate 36, thereby providing a construction in which the tightening of the tension members is accomplished from the floor of the car by screwing up the nut 37 of the eye bolt.

Instead of passing the flexible tension 55 members over the hubs of the vehicle, as shown in Figs. 2 and 9, we may hold the hub of the vehicle in place by means of a bolt extending through the arms 17 of the form of cap shown in Fig. 3, or through upwardly extending sides 38 of the cast metal 60 form of head shown in Fig. 7. In this last mentioned case two tension members are preferably used in connection with each supporting or strut member, the upper end of 65 said members being fastened by passing

them through holes 39 and twisting their free ends around the said members the same as is illustrated in Fig. 6. The bolt above referred to is shown at 40 in Fig. 7, and, while it is shown as used only in connection 70 with a cast metal form or head, it may be used in connection with the form of head shown in Fig. 3 as above pointed out.

Fig. 8 shows a form of anchor made from a flat piece of metal the ends 41, 42 of which 75 are made to over-lie one another, thereby providing a loop 43, to which the lower ends of the flexible brace members may extend, the same as in the form of our invention 80 shown in Fig. 2.

In view of the foregoing premises it will be appreciated that the strut members and brace members may be readily assembled with one another and secured together, as by means of the bolt 25 above referred to; 85 and the metallic base members and hollow brackets at the ends of said members secured to the bottom and sides of the car; the securing of the said ends being accomplished by the use of comparatively small lag or 90 other screws or nails thereby providing a construction in which the car is not injured to any material extent, and at the same time a construction which permits the parts to be readily detached from the car and returned 95 to the shipper for re-use.

After the vehicle is in place and supported by the upper ends of the strut members the flexible tension members provide a scheme whereby the vehicle may be effectively braced against longitudinal or fore and aft movement, and a scheme wherein the hubs of the vehicles are at the same time and by the same bracing means held in place relative to the upper ends of the strut members; and these tension members, again, are of such form and construction that they may be readily attached to and detached from the floor of the car and used repeatedly.

Having thus described and explained our invention, we claim and desire to secure by Letters Patent:

1. In a car loading system for use in shipping motor vehicles in freight cars, inclined supporting or strut members extending upward from the floor and inward from the sides of the car; metallic base members secured one to the lower end of each of said strut members and provided each with a flange whereby said base members 120 may be fastened to the floor of the car; metallic cap members secured one to the upper end of each of said strut members and provided each with a seat adapted to receive and support the outer end of the hub 125 of a motor vehicle; brace members extending from the sides of the car inward and the inner ends of which are secured to the cap members at the upper ends of said strut members, and which brace members lie sub- 130

stantially in vertical planes extending through said strut members and through the axles of a motor vehicle supported by said strut members; and flexible tension members, one associated with each of said strut members, the middle portions of said tension members extending over the hubs of a motor vehicle supported by said strut members to thereby hold said hubs in the

members to thereby hold said hubs in the
10 seats aforesaid, and the ends of said mem-
bers being secured to the floor of the car at
two points spaced apart from one another
and located one in front and the other to
the rear of the lower ends of said strut
15 members.

2. In a car loading system for use in

20 the sides of the car; metallic base members secured one to the lower end of each of said strut members and provided each with means whereby said base members may be fastened to the floor of the car; metallic cap
25 members secured one to the upper end of each of said strut members and provided each with a seat adapted to receive and support the outer end of the hub of a motor vehicle; brace members extending from
30 the sides of the car inward and the inner ends of which are connected one with each of said strut members adjacent its upper

end to thereby prevent outward movement thereof; and flexible tension members, one associated with each of said strut members, the middle portions of said tension members being connected with the upper ends of said strut members, and the ends of said flexible members being secured to the floor of the car at two points spaced apart from one another and located one in front and the other to the rear of the lower ends of said strut members.

3. In a car loading system for use in
45 shipping motor vehicles in freight cars, incl-
ined supporting or strut members extend-
ing upward from the floor and inward from
the sides of the car; metallic base members
50 secured one to the lower end of each of said
strut members and provided each with
means whereby said base members may be
fastened to the floor of the car; metallic
cap members secured one to the upper end
55 of each of said strut members and provided
each with a seat adapted to receive and
support the outer end of the hub of a motor
vehicle; brace members extending from the
sides of the car inward and the inner ends
60 of which are connected one with each of
said strut members adjacent its upper end
to thereby prevent outward movement there-
of; and flexible tension members, one asso-
ciated with each of said strut members, the
middle portions of said tension members

extending over the hubs of a motor vehicle 65 supported by said strut members to thereby hold said hubs in the seats aforesaid, and the ends of said flexible members being secured to the floor of the car at two points 70 spaced apart from one another and located one in front and the other to the rear of the lower ends of said strut members.

4. In a car loading system for use in shipping motor vehicles in freight cars, inclined supporting or strut members extending upward from the floor and inward from the sides of the car; means whereby the lower ends of said strut members may be fastened to the floor of the car; means at the upper ends of said strut members for supporting the outer ends of the hubs of a motor vehicle; brace members extending from the sides of the car inward and the inner ends of which are connected one with each of said strut members adjacent its upper end to thereby prevent outward movement thereof, and which brace members lie substantially in vertical planes extending through said strut members and through the axles of a motor vehicle supported by said strut members; and flexible tension members, one associated with each of said strut members, the middle portions of said tension members extending over the hubs of a motor vehicle supported by said strut members and the ends of said members being secured to the floor of the car at two points spaced apart from one another, and located one in front and the other to the rear of the lower ends of said strut members. 100

5. In a car loading system for use in
shipping motor vehicles in freight cars,
supporting or strut members extending up-
ward from the floor of the car; means
whereby the lower ends of said strut mem-
bers may be fastened to the floor of the
car; means at the upper ends of said strut
members for supporting the outer ends of
the hubs of a motor vehicle; brace mem-
bers extending from the sides of the car 110
inward and the inner ends of which are con-
nected one with each of said strut mem-
bers adjacent its upper end to thereby pre-
vent outward movement thereof; and flexi-
ble tension members, one associated with 115
each of said strut members, the middle
portions of said tension members extending
over the hubs of a motor vehicle sup-
ported by said strut members and the ends
of said tension members being secured to 120
the floor of the car at two points spaced
apart from one another and located one in
front and the other to the rear of the lower
ends of said strut members.

In testimony whereof we affix our signatures. 125

GILBERT P. MARINIER.
EDWARD E. CHRYSLER,
